UNITED STATES PATENT OFFICE.

HEINRICH SCHRAMM, OF NUEREMBERG, GERMANY, ASSIGNOR OF ONE-HALF
TO LEONHARD SCHMIDT, OF NUEREMBERG, GERMANY.

CROSSBOW.

SPECIFICATION forming part of Letters Patent No. 728,504, dated May 19, 1903.

Application filed October 30, 1902. Serial No. 129,424. (No model.)

To all whom it may concern:

Be it known that I, HEINRICH SCHRAMM, founder, a subject of the King of Bavaria, residing at No. 6^a Solgerstrasse, Nuremberg, 5 Bavaria, Germany, have invented certain new and useful Improvements in Crossbows; and I do hereby declare the following to be a full, clear, and exact description of the invention, such as will enable others skilled in the art to 10 which it appertains to make and use the same.

Heretofore it has been well known in this art to combine with hand-arms used for toys and sports an appliance for throwing balls and the like, as may be seen on reference to German Patent No. 97,554; but so far many disadvantages have existed which rendered its use with any degree of accuracy almost impossible. To this type of device it was also the practice to apply a net or any other suitable device for catching the balls, for instance, from an opponent in a game played with these devices or when shooting the balls in the air. Such an attachment is seen in German Patent No. 91,493; but these devices 25 have been heretofore too complicated and unwieldy for use by children.

The object of my invention is to produce a new and improved contrivance which may be used equally as well as a toy and in sports, 30 and owing to the simplicity of the device the cost of manufacture of the same is much cheapened.

In the accompanying drawing my improved crossbow is shown in a view from above, parts 35 broken away.

a is the shaft of a crossbow, being connected to a tube *b*, in which slides the shoot-bolt *c*, guided therein by pins *c'*, extending on both sides of the bolt through the slots *b'* of the tube *b*. The bolt is driven by a bow *d*, 40 fixed on the tube and being operated by a trigger *f*. To the top of the tube is secured a holder *h*, receiving the ball *g* and holding it in position so that the bolt *c* when driven outward will hit the ball and dart it away. 45 The bolt itself is fixed to the traverse *d'* and does not fly out of the tube. A net *i*, fixed on the top edge of the tube, is to catch the ball if the crossbow is employed in sport.

What I claim, and desire to secure by Letters Patent, is—

In a device of the type set forth, the combination with a shaft of a crossbow, a tube having parallel slots in the sides thereof mounted thereon, bow-arms secured to the tube at opposite points thereon, a bolt slidingly mounted within said tube, pins formed thereon adapted to slide in the slots of the tube, a transverse bar secured to the rear of said bolt, connecting means between said transverse bar and the said bow, and a ball-holder secured to the tube having catching means extending outwardly therefrom, substantially as described.

In testimony whereof I affix my signature 65 in presence of two witnesses.

HEINRICH SCHRAMM.
